REFRIGERATION VAPORIZER

Filed March 25, 1927

Inventor
W. O. Voss.

By Bacon & Thomas

Attorney

UNITED STATES PATENT OFFICE

WILLIAM O. VOSS, OF YORK, PENNSYLVANIA, ASSIGNOR TO MARTIN-PARRY CORPORATION, OF YORK, PENNSYLVANIA, A CORPORATION OF DELAWARE

REFRIGERATION VAPORIZER

Application filed March 25, 1927. Serial No. 178,422.

This invention relates to refrigerating systems of the compressor-condenser-expander type.

The primary object of the invention is to provide a vaporizing element comprising a tank and an improved arrangement of tubing connected therewith whereby to increase the surface exposed to the air and secure a more effective and rapid freezing of the ice in the trays provided for such devices.

More specifically, the invention comprehends the provision of a group of substantially U-shaped tubes longitudinally disposed with respect to the longitudinal axis of the tank and both ends of each of said tubes being secured to the same side of the tank.

Still another object of the invention is to provide two groups of said tubes, longitudinally disposed as aforesaid, one group having the ends of the tube secured to one side wall of the tank, and the other group having the ends of the tubes secured to the opposite side of the tank.

Still another object of the invention is to bend the lower ends of certain of said tubes of said groups inwardly, toward each other, to define a chamber between the two groups of tubes and the tank.

Numerous other objects of the invention will be readily apparent to those skilled in the art from the following description, taken in conjunction with the drawings attached hereto and forming a part thereof, in which

Fig. 1 represents an end view,

Fig. 2 is a longitudinal view partly in section of the tank and tube arrangement, and

Fig. 3 is a detailed view partly in section of the expansion coil structure.

Referring now specifically to the drawings, wherein like reference characters represent like parts, 1 represents the vaporizing tank provided with headers 2 and 3. The tank portion is preferably secured to these headers by inturning the marginal portions thereof as at 4 and 5, although it is obvious that any other connecting arrangement may be employed.

To the header 3 is preferably secured a closure (not shown) for conducting the vaporized refrigerating medium from the tank

to the compressor and for returning the liquefied refrigerating medium from the condenser to the tank, as is well known in the art. The tank is preferably provided with a float arrangement for maintaining a predetermined level of the liquid refrigerant in the said vaporizing tank, but as float arrangements of this character are well known in the art and form no part of this invention, it has not been specifically disclosed in the drawings.

In carrying out my invention, I provide several groups of substantially U-shaped tubes, longitudinally disposed with respect to the tank, as distinguished from transversely arranged, and each of these groups of tubes have both of their ends secured to the same side wall of the tank. The tubes referred to are designated by reference numerals 6, 7, 8, and 9, the ends of which are secured to the tank in substantially the same general longitudinal plane as at 10, 11, 12, 13, 14, 15, 16, and 17. These tubes are preferably of differential lengths and capacities. Thus, the nested tubes are progressively increased in capacities from the central tube 6 to the outer tube 9. The tubes 6 and 7 are preferably arranged in a true vertical plane, one within the other, as shown in the drawings, while the tube 8 is slightly turned inwardly at its lower bent portion as at 18. The outer tube 9 surrounding each of the tubes 6, 7, and 8 aforesaid, is preferably bent inwardly at its lower portion to a greater extent, as shown at 19.

I preferably provide two groups of said tubes, one secured to one side wall of the vaporizing tank and the other group of tubes therein secured to the adjacent side wall of the tank, and the inner ends of both of the larger tubes, of said groups, are turned inwardly toward each other in order to define a chamber 20 therebetween for freezing purposes.

The drawings attached hereto represent the preferred form of the invention, but it is understood that various changes in the arrangements of the parts may be made without departing from the spirit of the invention as defined in the following claims.

Having thus described the invention, what I claim is:

1. In a vaporizer for refrigerating systems, the combination with a vaporizer tank, a group of substantially U-shaped tubes connected with said tank, and longitudinally disposed with respect to the longitudinal axis of the tank, said tubes having each of their ends secured to the same side wall of the tank, and at least some of said tubes being bent inwardly at their lower portions to define a chamber.
2. In a vaporizer for refrigerating systems, the combination with a vaporizer tank, several groups of vaporizer tubes attached to said tank at opposite points thereof, each of said groups of tubes being disposed longitudinally with respect to the longitudinal axis of the vaporizer tank, and at least one of said tubes of each group being bent inwardly at their lower portions, toward each other, to thereby define a chamber between the expansion tank and the said tubes.
3. In a vaporizer for refrigerating systems, the combination with a vaporizing tank, a group of superimposed vaporizer tubes connected with one side of the tank and depending therefrom, said tubes being mounted in a longitudinal direction with respect to the longitudinal axis of the tank, and a second group of superimposed nested vaporizer tubes having their ends secured to the adjacent wall of the vaporizing tank and depending therefrom in parallel relationship with the first named group of tubes, thereby to define a space between the several groups of tubes.
4. In a vaporizer for refrigerating systems, the combination with a vaporizer tank, several groups of nested vaporizer tubes attached to said tank at opposite points thereof and depending therefrom, each of said groups of tubes being disposed longitudinally with respect to the longitudinal axis of the vaporizer tank, and defining a chamber between the expansion tank and said groups of tubes.
5. In a vaporizer for refrigerating systems, the combination with a vaporizer tank, several groups of vaporizer tubes attached to said tank at opposite points thereof and depending therefrom, the tubes in each of said groups having differential capacities and being in substantially nested disposition, said groups of tubes being spaced apart to thereby define a chamber therebetween.
6. A cooling unit for refrigerators, comprising a cooling compartment, a header arranged over said compartment, and a plurality of refrigerant conducting tube loops each of which has upright sections arranged adjacent to the same side of said compartment and both connected at their upper ends with the same side of said header and the lower parts of said upright sections being connected by a return bend which is arranged underneath said compartment, said upright sections being arranged transversely in line with each other.

7. A cooling unit for refrigerators, comprising a cooling compartment, a header arranged over said compartment, and a plurality of refrigerant conducting tube loops each of which has upright sections arranged adjacent to the same side of said compartment and both connected at their upper ends with the same side of said header and the lower parts of said upright sections being connected by a return bend which is arranged underneath said compartment, said upright sections being arranged transversely in line with each other.

8. A cooling unit for refrigerators, comprising a cooling compartment, a header arranged over said compartment, and a plurality of refrigerant conducting tube loops each of which has upright sections arranged adjacent to the same side of said compartment and both connected at their upper ends with the same side of said header and the lower parts of said upright sections being connected by a return bend which is arranged underneath said compartment, said upright sections being arranged transversely in line with each other, and the upper ends thereof being turned inwardly toward said header.

9. A cooling unit for refrigerators, comprising a cooling compartment, a header arranged above said compartment, and a plurality of refrigerant conducting tube loops each of which has upright sections arranged adjacent to the same side of said compartment and connected at their upper ends by the header and at their lower parts by a return bend which extends underneath said compartment and the parts of which are arranged horizontally side by side.

10. A cooling unit for refrigerators comprising a header, a plurality of nested tubes connected with said header and arranged to provide a row of tubes extending longitudinally with respect to the axis of the header, a second row of longitudinal nested tubes laterally spaced from said first row of tubes, the ends of one row of tubes communicating with one side of the header and the ends of the second row of tubes communicating with another side of the header.

11. A cooling unit for refrigerators comprising a header, a plurality of nested tubes having their ends connected to and communicating with the header on one side thereof and arranged to provide a row of tubes extending longitudinally with respect to the axis of the header, a second row of nested longitudinal tubes laterally spaced from said first row of tubes and having their ends communicating with another side of the header, the rows of tubes being spaced to define a compartment adapted to receive a cooling receptacle.

In testimony whereof I affix my signature.

WILLIAM O. VOSS. 130
